UNITED STATES PATENT OFFICE.

FRED JANDT, OF LA CROSSE, WISCONSIN.

DESIGN FOR A PICTURE-FRAME.

No. 39,463.

Specification for Design.

Patented Aug. 25, 1908.

Application filed April 16, 1908. Serial No. 427,541. Term of patent 7 years.

To all whom it may concern:

Be it known that I, FRED JANDT, citizen of the United States, residing at La Crosse, in the county of La Crosse and State of Wisconsin, have invented a new, original, and ornamental Design for Picture-Frames, of which the following is a specification, reference being had to the accompanying drawings, forming a part thereof.

Figure 1 is a front view of a picture frame showing my new design, and Fig. 2 is an edge view thereof.

The essential feature of the design is a frame of oblong and rectangular form, the bars constituting the sides thereof having their outer edge portions regularly fluted or crimped, presenting a substantially uniform appearance in edge view. The inner portion

of each bar comprises a plain part adjacent to the crimped or fluted portion and a molded edge portion bordering upon the opening.

Having thus described the invention, what is claimed as new is:

The ornamental design for a picture frame substantially as shown and described, said frame being of oblong and rectangular outline and having the outer portion of its bars crimped or fluted and having the inner edge portion of the bars molded and the part intermediate of the molded and crimped portions plain.

FRED JANDT. [L. s.]
